UNITED STATES PATENT OFFICE.

JOHN FLINDALL, OF CHICAGO, ILLINOIS.

ADJUSTABLE SUPPORT FOR CHAIRS.

No. 805,846.

Specification of Letters Patent.

Patented Nov. 28, 1905.

Application filed February 18, 1904, Serial No. 194,219.

To all whom it may concern:

Be it known that I, JOHN FLINDALL, a citizen of the United States, residing at Chicago, county of Cook, State of Illinois, have invented 5 a certain new and useful Improvement in Adjustable Supports for Chairs; and I declare the following to be a full, clear, and exact description of the invention, such as will enable others skilled in the art to which it pertains to 10 make and use the same, reference being had to the accompanying drawings, which form a part of this specification.

My invention has for its object the production of an adjustable support for a chair or 15 other seat. In the drawings I have shown it as applied to a rocking-chair; but it is obvious that it can be applied to any other form of chair without departing from the spirit of the invention.

20 In the drawings, Figure 1 is a side elevation of my chair; Fig. 2, a sectional view on the line 2 2 of Fig. 1, and Fig. 3 a sectional view on the line 3 3 of Fig. 1.

In carrying out the invention, A represents 25 the seat or other support for the chair. Engaged to the bottom thereof are what may be termed "channel-irons," shaped to provide a horizontal groove a.

B is an iron having extensions b, which enter the channel a and slide therein.

b' represents ears depending from the piece B, one set at each end of the piece, and between those of each set is pivoted the end c of one 30 of the supports C, the pivot being the rod D.

35 Engaged to the back of the seat A are depending ears E, in which the end f of the support F is pivoted, the two supports being pivoted together at f'. Engaged to the back portion of the seat A is a piece G, preferably, 40 although not necessarily, made of spring metal at g, so that the outer free end can be tilted. Of course the tilting movement may be obtained in other ways without departing from the spirit of the invention; but I prefer to 45 make the piece G of spring metal, as above described. The free end of each piece G is provided with teeth g' to form a rack, the two pieces G having their rack-teeth engaging the rod D and engaged together by the rod G', 50 which also forms a handle to lift the two racks simultaneously.

H represents the rocker on one side of the chair, although this instead of being curved might also be any other suitable form. Engaged to the end of the support H is a piece H', having a curved end h'. The lower end

of the supporting-piece F rests in this curved end h' of the piece H' and is engaged to the supporting-piece H by the bolt h''. The lower end of each support C has a sliding engagement with the rocker H, as shown in Fig. 3. Engaged to the support C by the bolt J is a cross-piece K. Engaged to the rocker H in any suitable manner is a strip L. The cross-piece K has depending lugs k, containing horizontal recesses k', which engage over the projecting edge of the strip L, so that the support C has a sliding engagement with the rocker H.

The operation will be readily understood. 70 The operator grasps the rod G' and lifts the rack-bar, so that the teeth clear the rod D, when the chair can be adjusted to any height desired, and then the racks are dropped onto the rod, and this locks the chair at the desired 75 elevation. It is of course obvious that in raising the chair the rack-bars need not be touched by the operator, since the beveled faces of the teeth will enable them to slide over the rod D.

It is obvious that the supporting-pieces C 80 and F may be made of any desired shape; but I prefer to turn the lower portion of the body of each piece at right angle to itself, so that there will be formed the spring portions C' and F'. It is also obvious, of course, that the 85 many details of construction can be changed or altered without departing from the spirit of the invention.

What I claim is—

1. In a rocking-chair, the combination with 90 a seat, of a pair of rockers, an adjustable support interposed between each side of said seat and one of said rockers comprising a pair of members pivotally united, means for securing the lower end of one member of each pair to 95 a rocker, means for pivotally securing the upper end of said member to the seat, means for securing the lower end of the second member of each pair in sliding engagement with the rocker, means for positively securing the upper end of said second member of each pair 100 in sliding engagement with the seat, and a yielding rack-bar secured to the seat for retaining the upper end of the second member of each pair in the desired adjusted position. 105

2. In a chair or the like, the combination with the base thereof and a suitable support or supports to rest on the floor, of an adjustable support between the two comprising two sets of members, each set consisting of 110 two members pivoted together in the form of a letter X, the lower end of one member hav-

ing a sliding engagement with the stationary support while the lower end of the other member is also engaged to said support, the upper end of one member pivoted to the base 5 of the chair, while the upper end of the other member is engaged by a rod to the upper end of the corresponding member on the other side, two rack-bars, one engaged to each side of the base connected together by a rod, the 10 teeth on the rack-bars depending downwardly

and adapted to engage the connecting-rod between the two supporting members and means for holding said connected upper ends in sliding engagement with the base.

In testimony whereof I sign this specifica- 15
tion in the presence of two witnesses.

JOHN FLINDALL.
